UNITED STATES PATENT OFFICE.

MAX R. SLOUGH, OF COVINA, CALIFORNIA.

DETACHABLE SANITARY COVERING FOR TOILET-SEATS.

972,269.

Specification of Letters Patent. Patented Oct. 11, 1910.

Application filed June 12, 1909. Serial No. 501,862.

To all whom it may concern:

Be it known that I, MAX R. SLOUGH, a citizen of the United States, residing at Covina, in the county of Los Angeles and 5 State of California, have invented new and useful Improvements in Detachable Sanitary Covering for Toilet-Seats, of which the following is a specification.

My invention relates particularly to a 10 sanitary covering for water-closet seats, and a prime object thereof is to provide a base member having a plurality of coverings detachably secured thereto, one of which may be readily removed therefrom every time 15 that the closet is used, and which are absolutely sanitary, the coverings being so arranged that the ones directly below the uppermost one will not be brought in contact with the body of the person using the closet.

20 A further object is to provide a covering that may be readily secured to and removed from a toilet seat and one in which a covering may be detached from the others in an expeditious manner.

25 In the accomplishment of the above objects I preferably employ a base member formed from card-board or other similar material and stamped into approximately the general configuration of a toilet-seat. I also provide 30 a plurality of sanitary sheets detachably secured to the base member, provision being made whereby they may be easily detached therefrom. Means are provided to maintain the base member in rigid relation to the seat, 35 while the same is being used.

I accomplish the above objects by means of the device hereinafter described and illustrated in the annexed drawings, in which:—

40 Figure 1—is a plan view of a typical water-closet seat with my device secured thereto. Fig. 2—is a bottom plan view of the seat shown in Fig. 1. Fig. 3—is a perspective sectional detail of a portion of a closet bowl and seat with my device attached 45 thereto.

In a practical embodiment of my invention, as illustrated in the drawings, 5 designates a closet-bowl of usual construction, provided with a hinged seat 6, the upper face 50 rounding transversely, as clearly illustrated in the drawings. The under face of this seat is provided with the usual elastic cushioning devices 7 that serve to raise the seat out of contact with the upper edge of the bowl.

55 My device, as heretofore stated, consists primarily of a base member 8 formed of a

pliable material, such as heavy paper, and stamped by means of a die into the configuration of the upper face of the seat 6. Detachably secured to the upper face of this 60 member are a plurality of covers 9 which are preferably formed from thin oiled or paraffin paper, that will prevent the absorption of any moisture, and thereby prevent the communication to the covers directly beneath the uppermost one. These covers are, as has been said before, preferably formed of exceedingly thin paper, so that the maximum number may be secured to the base member or pad. The covers are preferably 65 secured to the pad and to each other by means of an adhesive 10 at various points along its edges, as clearly illustrated in Fig. 2 of the drawings. The purpose of applying the adhesive at certain points along the 70 edge, instead of applying it to the entire edge as is usual in padding paper, is to render the removal of the uppermost sheet a comparatively simple operation, each sheet being detached therefrom much more readily 75 than if the entire edges were supplied with the adhesive. Each sheet is preferably provided with a tab 11 that is intended to facilitate the removal of the separate sheets 80 from the device, each tab being formed integral with its sheet.

In order to prevent any movement of my device while in place on the seat, I have provided the base member 8 with a series of tabs 90 12 formed of a suitable fabric and provided with a buttonhole 13. These tabs are preferably secured to the member on its inner edge, and are designed to engage buttons or other suitable securing means 14, which are attached directly and at right angles to the 95 under face of the toilet-seat, the methods of attachment being clearly illustrated in Figs. 2 and 3 of the drawings.

It will be apparent from the above description that I have produced a device 100 which will render completely sanitary public closets, and from which individual sheets or covers may be readily removed therefrom.

Having described my invention what I claim as new and desire to secure by Letters 105 Patent is:—

1. A supplementary seat for toilet-seats, comprising in combination a toilet-seat provided with attaching means, a base member provided with a plurality of covers formed from a sanitary material adhesively secured thereto along their edges, and a plurality of 110

button-holed tabs secured to said base member and adapted to engage the attaching means secured to the toilet-seat.

2. A supplementary seat for toilet seats, comprising in combination a toilet seat provided with a plurality of attaching pins secured to the under face thereof, a base member formed of a fibrous material and provided with a plurality of sanitary covers secured to the upper face of the base member and adhesively secured at a plurality of points along their edges, and a plurality of button-holed tabs secured to said base member, said tabs adapted to engage the pins secured to the under face of the toilet-seat.
3. A supplementary seat for toilet seats, comprising in combination a main toilet seat provided with a plurality of attaching

means, a supplementary seat comprising a base member formed of a fibrous material and provided with a plurality of covers formed from a sanitary material, said covers adhesively secured to the base member at a plurality of points along their edges, and means secured to the base member and adapted to engage the attaching means secured to the toilet seat, whereby the base member is held in detachable relation to the seat.

In witness that I claim the foregoing I have hereunto subscribed my name this 8th day of May, 1909.

MAX R. SLOUGH.
